UNITED STATES PATENT OFFICE.

JOSEPH A. GROEBLI, OF NEW YORK, N. Y., ASSIGNOR TO THE KURSHEEDT MANUFACTURING COMPANY, OF SAME PLACE.

FABRIC-PUFFING MACHINE.

SPECIFICATION forming part of Letters Patent No. 599,328, dated February 22, 1898.

Application filed June 11, 1896. Serial No. 595,077. (No model.)

To all whom it may concern:

Be it known that I, JOSEPH A. GROEBLI, residing in the city, county, and State of New York, have invented certain new and useful 5 Improvements in Fabric-Puffing Machines, of which the following is a specification.

My invention relates to fabric-puffing machines, and has for its object to produce a machine wherein fabric may be puffed or 10 crimped or fluted.

My invention has for its special object to produce a machine which will crimp or flute the fabric without tearing it.

In order that the invention may be fully understood, I will state that as at present constructed crimping rolls or devices have a number of teeth in contact acting on the fabric. The fabric coming to the crimping-roll is drawn in around the teeth as they are about 15 to mesh and pass through the rolls. It will be obvious that the teeth of the rolls at the point or line where the rolls are diametrically opposite to each other—that is to say, in the plane of the axes of the rolls—are more 20 deeply in mesh than the teeth are where the fabric first enters the rolls. Consequently the teeth where the fabric first enters the rolls not at that moment meshing with each other to the full extent a less quantity of fab- 25 ric than is necessary to reach entirely to the bottom of the grooves between the teeth will be drawn in, so that as the rolls revolve and draw the fabric in there will not be sufficient fabric drawn in by the first teeth coming in 30 mesh to extend entirely around the teeth when they reach the plane of the axes of the rolls, and consequently in order to accommodate itself to the rolls the fabric must either stretch or tear when it reaches the plane of 35 the axes. In order to obviate this difficulty, it is necessary to bring the fabric to the main crimping-rolls in a crimped condition, so that the teeth as they come into mesh will take a greater quantity of fabric in than the extent 40 of their meshing, (this they do by virtue of the fact that the preliminary crimpler, hereinafter referred to, has already crimped the fabric,) so that as the rolls continue to revolve there will be sufficient fabric drawn in 45 to extend around the teeth when they reach the plane of the axes of the rolls, which is

their line of greatest mesh. I have been to some pains to describe this operation in order to make it perfectly apparent that I am not seeking to aggregate two sets of crimping-rolls, but merely to provide a preliminary crimpler whereby the fabric may be given a crimp of full depth without tearing the goods and to thereupon pass the goods in a crimped condition to the main crimping-rolls in order 55 to enable the main crimping-rolls, which have several teeth in mesh, to take up a sufficient quantity of fabric to enable the crimping to be done without injury to the fabric.

My invention will be understood by referring 60 to the accompanying drawings, in which—

Figure 1 is a plan view of a puffing-machine embodying my invention. Fig. 2 is a section on line 2 2 of Fig. 1, and Fig. 3 is a detail view 70 showing a crimping wheel or roll with a preliminary crimpler in co-operative relation therewith and a guide and conductor for the material to be crimped.

In the drawings, 1 1 are standards having 75 the inclined ways 2 2 and a cap 3. Working in the ways in the standards are bearing-blocks 4 5, which carry hollow shafts 6 7, which carry the crimping or fluting rolls or wheels 8 9. These crimping or fluting rolls 80 are shown as comprising a plurality of toothed sections 10 11 12 13 14 15 16 17 18 19 20 21 22 23, with intervening plane or curved sections 24 25. The toothed portions of these crimping-rolls mesh with each other, so that the upper 85 roll is driven from the lower, or vice versa, the upper bearing 5 being provided with an adjusting-rod 26, (having the intervening spring 27,) passing through the cap 3 for the purpose of adjusting it to regulate the extent of the 90 meshing of the rolls. Mounted in front of these rolls is a fabric-conductor, shown in the present instance as consisting of an undulated fabric-conductor 28 for bringing the fabric up to the crimping-rolls, the said guide 95 being also, if desired, provided with guide-bars 29 43, between which the fabric enters. This conductor may be supported in any suitable manner, as by means of a bed-block 30, pivoted to the frame 1 by the pivot 32, or 100 otherwise supported. The machine is also preferably provided with a curved guide or

guides 31, shown in the present instance as consisting of a plurality of upwardly-curved teeth for the purpose of supporting the fabric in its path from the preliminary crimper 5 to the main crimping-roller. The conductor for the fabric may also be provided with a brace 33 for entering the eyes 34 in order to adjust the inclination of the fabric-conductor. In proximity to the conductor and meshing with the first of the fluting or crimping rolls, being the one first reached by the fabric, is a preliminary crimper, shown in the present instance as a star-wheel 35, whose shaft is supported by the curved guides 31 and 15 which meshes with a few, say two, of the teeth of said crimping or fluting roll and is driven therefrom. The function and purpose of this preliminary crimper is to give to the fabric a preliminary crimp before it enters between 20 the crimping-rolls 8 9, which have several sets of teeth in mesh, so that when it enters between the crimping-rolls which have several teeth in mesh the strain upon the fabric in the rolls will be minimized, for it will be 25 obvious that where several teeth of the main rolls are in mesh the goods in traveling between the rolls will be thereby stretched and torn unless the said goods come to the said rolls in a crimped condition.

30 It will be observed that the teeth of the preliminary crimping-wheel 35 enter between the teeth of the main crimping-roller 9 to a less extent than do the teeth of the other main crimping-roller 8. This is the preferred arrangement for obvious reasons. By my invention, however, when the preliminary crimp has been given, while there is as yet no strain, the fabric comes into the main crimping-rolls in a crimped condition and in 35 sufficient length to take the permanent crimp imparted by the main crimping-rolls without stretching or tearing.

Located between the toothed portions of the lower crimping-roll and bearing upon the periphery of the said roll is a series of cloth-pressers 36, which are adjustable by means of the pivoted frame 37 and the set-screws 38 and spring set-screw 39 in the frame of the machine. The crimping-rolls, which constitute the main working part of the machine, may be driven in any suitable manner, as by means of the gearing 40 41, which is shown in dotted lines in Fig. 2 and in full lines in Fig. 1. One or more of the crimping-rolls 45 may be provided with a suitable heating means, such as a steam-supply 42.

The operation of the device shown is as follows: The fabric comes to the machine in the direction indicated by the arrow in Fig. 2 and 50 passes between the guide-bars 29 43 to the fabric-conductor 28, and as the conductor 28 is ridged or undulated the fabric will follow the contour of the said undulations and the machine will take in a fabric considerably 55 wider than itself, this occurring by reason of the undulations. From the conductor the fabric passes between the crimping-roll 9 and

the preliminary crimper or star-wheel 35, which, as before mentioned, meshing but a few teeth at a time with the crimping-roll 9, 70 will impart to the fabric a preliminary crimp without stretching or straining the said fabric. The preliminarily-crimped fabric now passes between the main crimping-rolls 8 9 and is given its final crimp or flute. It will 75 be observed that the toothed portions of the main crimping-rolls are placed side by side in pairs, leaving an untoothed space 24 25 between the pairs and a space 44 between the individuals of the pair of toothed portions. 80 In this space 44 the pressers 36 work, which pressers have the effect of pressing down the crimp or flute to receive the stitch, which is subsequently passed through by a sewing-machine in order to hold the crimps in place 85 so that the fabric will not resume its original form but will remain in the condition of a puffed fabric.

What I claim as new, and desire to secure by Letters Patent, is— 90

1. The combination of toothed crimping or fluting devices meshing with each other and arranged to crimp a fabric laterally, a toothed preliminary crimper engaging the fabric before it reaches the said crimping devices with 95 a less number of teeth than the fabric engages when in the said crimping devices and operating to crimp the fabric on lines running laterally to the direction of the feed of the fabric to such a degree as to adapt the said 100 fabric to fit into the crimping devices, all arranged so that the preliminary crimper will transmit a laterally-crimped fabric to the main crimping devices, which crimped fabric will be permanently crimped by the main 105 crimping devices.

2. The combination of crimping-rolls, a preliminary crimper placed in front of said crimping-rolls, and operating to crimp the fabric into such a form as will fit into the 110 crimping-rolls, all arranged so that the said preliminary crimper will impart a preliminary crimp to a fabric before it reaches the crimping-rolls, which said portion of the fabric containing the preliminary crimp will be finally 115 crimped by the crimping-rolls into the form originally imparted to it by the preliminary crimper, a presser, and means for compacting the fabric laterally, substantially as described. 120

3. The combination of toothed crimping or fluting devices meshing with each other and arranged to crimp a fabric laterally, a toothed preliminary crimper engaging the fabric before it reaches the said crimping devices with 125 a less number of teeth than the fabric engages when in the said crimping devices and operating to crimp the fabric on lines running laterally to the direction of the feed of the fabric to such a degree as to adapt the said fabric to 130 fit into the crimping devices, all arranged so that the preliminary crimper will transmit a laterally-crimped fabric to the main crimping devices, which crimped fabric will be per-

manently crimped by the main crimping devices, combined with mechanism for compacting the fabric laterally, substantially as described.

5 4. The combination of toothed crimping or fluting devices meshing with each other and arranged to crimp a fabric laterally, a toothed preliminary crimper engaging the fabric before it reaches the said crimping devices with 10 a less number of teeth than the fabric engages when in the said crimping devices and operating to crimp the fabric on lines running laterally to the direction of the feed of the fabric to such a degree as to adapt the said 15 fabric to fit into the crimping devices, all arranged so that the preliminary crimper will transmit a laterally-crimped fabric to the main crimping devices, which crimped fabric will be permanently crimped by the main 20 crimping devices, and an undulating guide for compacting or undulating the fabric laterally, substantially as described.

5. In a machine of the character described, the combination of crimping-rolls, means for 25 forming longitudinal puckers in the fabric, the said means also operating to conduct the fabric to the crimping-rolls, a preliminary crimper comprising a star-wheel meshing with one of the crimping-rolls to a less extent than 30 the crimping-rolls mesh with each other, whereby a preliminary crimp will be imparted to the fabric, which crimp is subsequently permanentized by the crimping-rolls, and a presser for pressing the crimps imparted to 35 the fabric.

6. In a machine of the character described, the combination of a fabric-conductor for bringing the fabric up to the crimping-rolls, a plurality of meshed crimping-rolls, a curved guide extending into the space between the crimping-rolls and a star-wheel supported by the curved guide. 40

7. In a machine of the character described, the combination of a fabric-conducting means for bringing the fabric up to the crimping-rolls, a plurality of meshed crimping-rolls, a guide 45 31 extending into the space between the meshed crimping-rolls, and a preliminary crimper meshing with one of the crimping-rolls and located between them. 50

8. In a machine of the character described, the combination of a plurality of meshed crimping-rolls, a fabric-conductor for bringing fabric up to the said crimping-rolls, a guide 55 extending from the fabric-conductor between the crimping-rolls, and a preliminary crimper carried by the guide.

9. In a machine of the character described, the combination of meshed crimping-rolls, a guide 60 31 extending into the space between the crimping-rolls, and a preliminary crimping-roll 35 meshing with one of the crimping-rolls and located intermediate of the ends of the guide, whereby the fabric may be preliminarily crimped and then carried by the 65 guide to the main crimping-rolls.
